BED ATTACHMENT

Henry M. Herbener, Thomasville, Ga.

Application May 5, 1939, Serial No. 272,003

8 Claims. (Cl. 24—72.5)

My invention relates to an attachment for a bed.

An important object of the invention is to provide an attachment which may be applied to a bed, and will prevent the bed covers from improperly slipping off of the bed, when the bed is occupied.

A further object of the invention is to provide a device of the above-mentioned character which will permit the bed covers being brought down over the edges of the mattress, springs or the like.

A further object of the invention is to provide a device of the above-mentioned character which is neat and attractive in appearance.

A further object of the invention is to provide a device of the above-mentioned character which may be readily applied to a spring, or a box spring, and not materially interfere with normal operations of the same.

A further object of the invention is to provide a device of the above-mentioned character, which is collapsible and will be substantially flat when collapsed.

Other objects and advantages of the invention will be apparent in the course of the following description.

In the accompanying drawing forming a part of this application and in which like numerals are employed to designate like parts throughout the same—

Figure 1 is a side elevation of attachments embodying my invention, showing them applied to a bed.

Figure 2 is a transverse vertical section taken on line 2—2 of Figure 1.

Figure 3 is a perspective view of the attachment removed.

Figure 4 is a transverse section through the bed, showing attachments applied thereto embodying a modification of the invention.

Figure 5 is a perspective view of one of the modified attachments, and

Figure 6 is a perspective view of a further modified form of attachment.

Shown in Figure 1 of the drawing, I arrange two of the attachments 10 at each side of the bed. Each attachment comprises an inverted U-shaped body portion 11, having vertical sides 12. These vertical sides extend downwardly and are bent upon themselves at 13, forming vertical arms 14. These vertical arms are spaced laterally from the sides 12 and form vertical pockets 15, for receiving the longitudinal edges of the covers.

In the first form of the invention, the sides 14 are separate, and their upper free ends are bent inwardly and downwardly to provide hooks 16, adapted to engage over the edge of a spring 17.

In the use of this form of the invention, one or more of the attachments 10 may be applied to either or both sides of the bed, and the upper ends of the U-shaped body portion 11 will project a suitable distance above the upper surface of the mattress and covers. In the use of a single bed, particularly if the user tosses in his sleep, the covers frequently slip off the bed. My attachments will engage the covers and prevent this slippage. Further, if desired, the edge of the covers may be tucked in between the U-shaped body portion 11 and the mattress. When the bed is being made, the edges of the covers are tucked in between the U-shaped body portion 11 and the mattress. The attachment is preferably made of a material which will be resilient, and hence the U-shaped body portion 11 will yield toward and away from the mattress. The lower ends of the sides 14 engage the frame of the spring or the side rails of the bed, as shown.

In the modified form of the invention, as shown in Figure 5, the arms 14 carry a U-shaped horizontal connecting member 18, which connect the arms 14. The connecting member 18 is relatively short and is adapted to be passed between the mattress and the box spring. Oppositely arranged connecting members 18 of opposed attachments are detachably connected by means of a flexible strap 19 or the like. The connecting member 18 is hinged to the arms 14, at 20, so that the connecting members may be folded back upon the sides 12, when the device is not in use.

All of the parts of the attachment remain identical with those shown and described in connection with the first form of the invention.

In Figure 6, I have shown a third modification of the invention. In this form of the invention the invented U-shaped body portion 11 embodies the sides 12, which are bent at their lower ends at 21 to provide vertical arms 22, arranged in the plane of the sides 12 and spaced longitudinally from the sides 12 and respect to the bed. This provides pockets 23 arranged in the plane of the attachment. The arms 22 are connected by a connecting member 24, hinged thereto at 25, and used in a manner similar to the connecting members 18. When the device is not in use, the U-shaped connecting members 24 are folded into the body portion 11 and

lie in the same plane therein. The collapsed device is entirely flat and may be conveniently stored between the mattress and the spring or box spring. If desired, hooks similar to the hooks 16 may be substituted for the connecting member 24.

In the use of the last form of the invention, as shown in Figure 6, one or more of the same may be applied to both sides of the bed, and the connecting member 24 shifted to the horizontal position and passed between the mattress and the box spring. The U-shaped body portion 11 will extend above the mattress and serve as a guard for the covers, and if desired, the covers may be passed down between the U-shaped body portion and the edges of the mattress and the box spring, the covers passing through the pockets 23 and outwardly about the arms 22.

All forms of the invention have their parts 20 preferably made of resilient material.

It is to be understood that the forms of my invention herewith shown and described are to be taken as preferred examples of the same and that various changes in the shape, size and arrangement of parts may be resorted to, without departing from the spirit of my invention or the scope of the subjoined claims.

Having thus described my invention, I claim:

1. An attachment for a bed for retaining the covers or the like thereon, comprising a resilient inverted U-shaped body portion having sides bent upon themselves at their lower ends to form arms, said arms being spaced from the sides and arranged in a separate plane from the sides, and a U-shaped member connected with the arms and adapted to be secured in place by a strap or the like.

2. An attachment for a bed for retaining the covers or the like thereon, comprising an upstanding inverted U-shaped body portion having sides which are bent upon themselves at their lower ends to provide arms which are spaced from the sides, and a U-shaped member pivotally connected with the arms and being adapted to be held in place by a strap or the like.

3. An attachment for a bed for retaining the covers or the like thereon, comprising an upstanding inverted U-shaped resilient member having sides bent upon themselves at their lower ends to provide arms, the arms being spaced from the sides and disposed in substantially the plane of the sides and forming pockets therewith, and a U-shaped member pivotally connected with the sides and foldable into the plane 55 of the sides.

4. An attachment for a bed for retaining the covers or the like thereon, comprising an upstanding inverted U-shaped body portion having substantially vertical sides which are bent 60 at their lower ends upon themselves to provide substantially vertical arms which extend upwardly from the lower ends of said sides to form

U-shaped pockets, the pockets being adapted to receive the edges of the covers, and substantially horizontal attaching means carried by said arms.

5. An attachment for a bed for retaining the covers or the like thereon, comprising an upstanding inverted U-shaped body portion having substantially vertical sides which are bent at their lower ends upon themselves to provide substantially vertical arms which extend upwardly from the lower ends of said sides to form 10 U-shaped pockets, the pockets being adapted to receive the edges of the covers, the body portion extending above the pockets and serving as stops to prevent the displacement of the covers, and attaching means secured to the upper 15 ends of said arms for retaining the attachment in place in use.

6. An attachment for a bed for retaining the covers or the like thereon, comprising an upstanding inverted U-shaped body portion having substantially vertical sides which are bent 20 at their lower ends upon themselves to provide substantially vertical arms which extend upwardly from the lower ends of said sides to form U-shaped pockets, the pockets being adapted to receive the edges of the covers, and downwardly facing hooks secured to said arms for retaining the attachment in place in use.

7. An attachment for a bed for retaining the covers or the like thereon, comprising a substantially vertical side member carrying at its lower end a substantially vertical arm, the side member and arm forming a U-shaped pocket to receive the edges of the covers, the side member being spaced laterally from the arm and extending above the same to serve as a stop for the covers, the arm being disposed in use in a plane inwardly of the plane of the side member, and attaching means secured to the upper end of the arm and extending inwardly 40 from the same.

8. An attachment for a bed for retaining the covers or the like upon a mattress supported by a spring or box spring, said attachment comprising an inverted substantially vertical U-shaped body portion having a length extending from a point near the bottom of the spring or box spring to a point above the upper surface of the mattress, said inverted U-shaped body portion having substantially vertical sides which are bent at their lower ends upon themselves to provide substantially vertical arms which extend upwardly from the lower ends of said sides to form U-shaped pockets, the pockets being arranged at an elevation substantially beneath the mattress to receive the edges of the covers, the body portion extending above the pockets and serving as stops to prevent the displacement of the covers upon the upper surface of the mattress, and means to retain the attachment in place, said means being arranged substantially beneath the mattress.

HENRY M. HERBENER.
